DESIGN FOR A GEM SETTING OR SIMILAR ARTICLE

Israel Roskin, New York, N. Y.

Application December 11, 1941, Serial No. 104,568

Term of patent 14 years

To all whom it may concern:

Be it known that Israel Roskin, a citizen of the United States and resident of New York city, in the county of New York and State of New York, has invented a new, original, and ornamental Design for a Gem Setting or Similar Article, of which the following is a specification, reference being had to the accompanying drawing, forming part thereof, in which

Fig. 1 is a top plan view of a gem setting showing my new design;

Fig. 2 is a side elevational view thereof; and
Figs. 3 and 4 are sectional views taken substantially along the lines 3—3 and 4—4 of Fig. 1.

I claim:

The ornamental design for a gem setting or similar article, substantially as shown.

ISRAEL ROSKIN.
